CONTROL APPARATUS FOR PUMPS

Harold Wheelock Fletcher, Houston, Tex., assignor to Hughes Tool Company, Houston, Tex., a Corporation of Texas

Application October 19, 1931. Serial No. 569,674

6 Claims. (Cl. 103—52)

My invention relates to pumps of the pneumatic swab type in which a freely movable swab plunger is employed to lift a load of liquid to the surface through pneumatic pressure.

5 In such apparatus the plunger is raised with its load of liquid through gas or air pressure below the plunger. Where gas is present in the producing formation, the gas is allowed to accumulate below the plunger and its load until it 10 exerts sufficient pressure to lift it to the surface. When the load is discharged and the plunger is forced past the outlet with sufficient force to compress the air and liquid in the closed upper end of the eduction tube, the trapped fluid above 15 the plunger will thus force the plunger valve open, allowing the plunger to fall. Where compressed air is used the operation is practically the same.

Due to the fact that the gas which lifts the 20 plunger must escape from behind the plunger after the load is discharged, the plunger will drop back before the gas under its accumulated pressure has had time to escape. If this gas is allowed to escape quickly it will interfere with 25 the dropping of the plunger and will blow it back up into the upper end of the tube. A choke is therefore employed in the discharge line from the pump to slow down the rate of discharge so that the plunger can fall through the escaping 30 gas and not be materially impeded.

Heretofore a choke valve has been employed in the discharge line but such a valve maintains a fixed opening which has to accommodate the 35 passage of both liquid and gas. When the choke is set for the liquid, it does not sufficiently choke down the flow of gas.

It is an object of the invention to provide a 40 valve in the discharge line of an apparatus of this character in addition to the usual choke, which valve will be responsive to the pressure of different fluids to slow down the flow of gaseous fluid, but will not greatly impede the passage of liquid.

45 I form in combination with the choke valve usually employed, an additional valve of the back pressure type, which together with the choke will control the discharge of liquid and gas to the desired rate.

50 I also provide means to prevent undue accumulation of gas in the well casing, so as to regulate the pressure of gas in the well.

In the drawing herewith, Fig. 1 is a broken 55 side view, largely in central vertical section, showing a well head equipped according to my

invention. Fig. 2 is a vertical section through the lower end of the eduction tube.

Fig. 3 is a sectional detail of the back pressure valve employed.

The pneumatic swab device to which my invention is applied is one now old in the art. It includes a well casing 1 having a casing head 2 with a lateral pipe 3 connected therewith. This pipe is ordinarily employed as an inlet for pressure fluid when necessary. It has a hand operated valve 5 therein and a relief valve 4 of any preferred form to relieve the gas pressure in the well when it exceeds the desired maximum amount.

The upper end of the casing head has a bonnet 6 threaded at its upper end at 7 to engage the upper section 8 of the eduction tube and form a seal therewith.

On the inner face of the casing head is a shoulder 9 to support the bushing 10 upon the eduction tube 11. Said bushing is connected with the tube and sustains the weight of the tube which extends downwardly into the well. Said tube has a strainer 12 connected therewith by means of a special coupling 13 having a stop spider 14 there-in.

70 The plunger 15 in the tube is of the preferred form with a valve 16 therein supported in open position upon the head 17 but adapted to close upwardly into the seat 18 when the stem 19 on the valve contacts with the stop 14.

The eduction tube has a closed upper end 8 which has a buffer 20 therein for the plunger. Lateral slots 21 in the tube provide outlets for the fluid to the outlet pipe 22 leading to storage.

75 In this discharge line may be a gate valve 23 to close down the well. There is also a choke device which may be connected in the line by closing a gate valve 24. This choke, shown at 25, is coupled in a bypass 26 connected to the discharge line at both sides of the gate valve 24. 80 The choke has been illustrated in the copending application of Norman H. Ricker, Serial No. 560,271, filed August 31, 1931. It includes a housing with a seat to receive a needle shaped valve operated by the stem 27 to provide an opening 100 through the bypass of the desired capacity.

I place a back pressure valve, the housing of which is shown at 28, in the bypass on the upstream side of the choke. In Fig. 3 it will be seen that this back pressure valve includes a valve 105 member 29 fitting within the seat 30 in a passage through the housing 28 and adapted to be held in its seat by a coiled spring 31 which is a comparatively strong spring opposing any but a small opening of the valve and adjustable as to ten-

sion by means of the plug nut 32 screwed within the threaded opening 34 in the housing. The valve has a stem 35 which is fitted through guide openings in the plug and the housing.

5 This valve is adapted to be opened by the pressure of the fluid passing through the discharge pipe and is not set very tightly. Liquid will tend to exert a pressure thereon which will unseat the valve to allow the liquid to pass in the quantity desired. The choke, however, will limit the 10 rate of flow to a predetermined amount by reducing the size of the passage to a fixed orifice thus allowing a small pressure drop across the valve 29. The gas or air will also unseat the valve 29, but as 15 it is more fluid and will flow faster, and the pressure thereon being the same, the valve will not unseat more than is necessary to allow the desired rate of flow of the gas. This is due to the 20 fact that the choke 25 will not greatly impede the flow of gas or air because of the greater fluidity of the air and there will be a marked pressure drop across the valve. As the spring 25 is strong, it will resist opening of the valve beyond a slight amount such as is desired. Thus the 30 flow of gas is choked down by the back pressure valve to the desired rate, and the liquid is choked down by the choke valve 25 to the desired rate of flow, and I am thus enabled to slow the discharge of both liquid and gas down so that it will 35 allow the plunger to fall in the tube after the load is relieved without danger of the plunger being blown up to the top repeatedly by the rise of the escaping gas after the load is discharged. The tension of the spring 31, being adjustable, it is possible to easily regulate the discharge flow of the gas to suit the conditions of gas pressure experienced in the well.

Thus, in use of the pneumatic swab device, I am enabled to prevent undue pressure in the well 40 through my relief valve. Further, in the operation of the plunger, the load of liquid above the plunger will be discharged slowly at the desired rate by the adjustment of the choke valve 25 and the rate of escape of the gas will be regulated by 45 the back pressure valve through the adjustment of the tension on the valve spring 31. The rate of operation can be controlled and the plunger is assured of falling directly to the bottom after

the valve 16 in the plunger has been forced open by the pressure of fluid trapped in the closed upper end 8 of the tube.

What I claim as new is:

1. A pneumatic swab device including a casing, 80 a casing head thereon, an eduction tube in said casing adapted to discharge liquid into said casing head, an outlet line from said casing head, a choke valve in said line and a back pressure valve between said choke valve and said casing head. 85

2. A pneumatic swab device including a casing, 90 a casing head thereon, an eduction tube in said casing adapted to discharge liquid into said casing head, an outlet line from said casing head, a choke valve in said line and a back pressure valve between said choke valve and said casing head, and means to adjust the pressure on said back pressure valve tending to hold it seated.

3. In a pneumatic swab device, a well casing, 95 a casing head thereon, an eduction tube in said casing and extending above said casing head, means to seal said casing head about said tube at the upper end thereof, said tube being formed to discharge into said casing head, a plunger in said tube, an outlet pipe from said casing head, 100 a bypass on said pipe, a choke valve in said bypass and a back pressure valve in said bypass adjustable to control the flow of gas therethrough.

4. The combination in the discharge line of a 105 pneumatic swab device of a choke device providing a fixed orifice for the control of the flow of liquid, and a back pressure valve adjustable to control the flow of gaseous fluid therethrough.

5. In a pneumatic swab device a well casing, a 110 casing head, a bonnet closing the upper end of said casing head, an eduction tube fitting through said bonnet into said casing, means to relieve excessive pressure in said casing, and means on said casing head to regulate the flow of liquid and separate means to regulate the flow of gaseous fluid. 115

6. In a pneumatic swab device a well casing, a casing head, a bonnet closing the upper end of 120 said casing head, an eduction tube fitting through said bonnet into said casing, and automatically operating means to relieve excessive pressure in said casing.
